UNITED STATES PATENT OFFICE.

JOHN W. KENDRICK, OF CHICAGO, ILLINOIS.

RAIL-SPACING DEVICE.

1,001,860.

Specification of Letters Patent. Patented Aug. 29, 1911.

Application filed September 29, 1908. Serial No. 455,238.

To all whom it may concern:

Be it known that I, JOHN W. KENDRICK, a citizen of the United States, residing at Chicago, in the county of Cook and State 5 of Illinois, have invented certain new and useful Improvements in Rail-Spacing Devices, of which the following is a specification.

The object of my invention is to provide 10 a device which shall be adapted to hold the two rails of a railway track spaced apart at a definite distance.

A further object of my invention is to provide such a device which may be capable 15 of quick application to the rails for the purpose of temporarily holding them in the desired spaced relation.

Still another object is to provide such a 20 device that may be very quickly removed from the rails after having served the purpose already stated.

These and other objects will be made apparent in the following specification and claims, when taken in connection with the 25 accompanying drawings, in which—

Figure 1 is an elevation of my device, certain of the parts being shown in section, as indicated by the line 1 in Fig. 2. Fig. 2 is a top plan view. Fig. 3 is an end elevation 30 of the device. Fig. 4 is a section taken on the line 4 of Fig. 1.

A particular purpose for which my device is well adapted is in connection with fastening the rails to the ties. After the 35 rails have been spaced apart at the required gage, the device of my invention may be fastened across to both rails so as to hold them definitely separated at the gaged distance while the rails are being spiked to the ties. Thereafter the device can quickly be removed and used at another point along the track for the same purpose.

In the particular embodiment of my invention which I have chosen to illustrate in 45 the drawings, a metal bar 16 is provided having a jaw 17 which is adapted to engage the base 18 of the rail 15 in the manner shown in Fig. 1. A member 19 has a hole 21 therethrough which has a sliding fit on the bar 16. From this member 19 a jaw 20 projects in opposition to the jaw 17 on the bar. Above the bar 16, the slide 19 has a transverse slot 22, one side of this slot being in the plane of the upper surface of the bar

16 and the opposite side of the slot being 55 inclined to said plane. A key or wedge 23 occupies the slot, having a head 24 at its larger end adapted to be struck by a hammer and having a cotter pin 25 through its smaller end so as to prevent complete withdrawal of the wedge 23 from the slot 22. The sliding member 19 has a knob 26 on the end opposite to the jaw 20, this knob being adapted to receive a direct hammer blow. An eye 27 is provided in the end of the bar 16. This is engaged by the eye 30 in the end of the link 31 which carries a spike or prong 32 at its end. Two other slides designated generally as 19' and 19'', each similar in every respect to the slide 19 that has already been described, are mounted on the intermediate portion of the rod 16, as shown in Fig. 1.

The two rails 15 having been spaced apart by a gage at the desired distance, the slide 19 having been pushed out against the cotter pin 35 and the two slides 19' and 19'' being positioned in proximity to the middle point of the bar 16, the bar 16 is passed transversely under the two rails and the jaw 17 is hooked over the outer base 18 of one rail. Then the slide 19 is advanced toward the outer base 18 of the other rail by striking it with a hammer on the head 26, thus causing the jaw 20 to clamp tightly on the base 18. Then the slide 19 is clamped securely in place on the bar 16 by striking the wedge on its head 24. Thereafter in exactly a similar manner, the two slides 19' and 19'' are clamped upon the respective 75 inner bases of the two rails and the slides themselves are locked in place on the bar 16. Then the bar 16 may be fixed relatively to the ties 33 by driving the prong 32, as 80 shown in Fig. 2. One purpose of this is to keep the rails properly aligned on the ties 85 while construction or other trains are passing thereover before the rails are spiked down. Furthermore, the rails 15 are definitely held in the desired space relation 90 while being spiked to the ties. Thereafter it is only the work of a moment to strike the wedges 23 on their smaller ends, thus releasing the slides 19, 19' and 19'' and then 95 sliding them back from the rails, whereupon the bar 16 may be immediately removed and applied farther along on the track. In practice, it may be desirable to 100 105

use several such bars 16, applying them simultaneously at points along the track, then spiking the section of track spaced by them and then reapplying the bars similarly on a consecutive section of the track.

It will be seen that I have provided a temporary rail spacer which can be applied to the rails in the least possible time, which holds them definitely spaced as long as may 10 be necessary for the purpose of spiking them, and which can then be removed with a minimum expenditure of time and effort. It can be used equally well with screw spikes or others and it does not mutilate or damage 15 the ties or sleepers.

I claim:

1. A device for spacing the two rails of a track, comprising a bar with a fixed jaw on one end and with three adjustable jaws 20 thereon to engage both of the rails and hold them in fixed relation to the bar, and wedges to lock said adjustable jaws at any desired point of adjustment along the length of the bar, said adjustable jaws having transverse 25 recesses to receive said wedges.

2. A device for spacing the two rails of a track, comprising a bar with sliding members thereon adapted to engage both of the rails and hold them in fixed relation to the 30 bar, each said sliding member having transverse recesses adjacent to the bar and wedges therein to lock it securely in place on the bar at any desired point of adjustment along the same.

3. A device for spacing the two rails of a track, comprising a bar with a sliding member thereon, said sliding member having a jaw to engage the rail and having a slot therethrough adjacent to the surface of the 40 bar, and a wedge in said slot, the surface of the bar adjacent to the wedge being uniform.

4. A device for spacing the two rails of a track, comprising a bar with a slide thereon, said slide having means to engage the rail 45 and a tapering slot therethrough adjacent to the surface of the bar, and an adjustable wedge in said slot, the surface of the bar adjacent to the wedge being uniform.

5. A device for spacing the two rails of a track, comprising a bar with adjustable 50 means thereon to engage both of the rails and hold them in fixed relation to the bar, and a hook pivoted to the bar and adapted

to engage the adjacent railway sleeper so as to hold the bar in fixed relation thereto. 55

6. A device for spacing the two rails of a track comprising a bar with slideable jaws mounted thereon to engage both of the rails and hold them in fixed relation to the bar, and a hook pivoted to the bar and adapted 60 to engage the adjacent railway sleeper so as to hold the bar in fixed relation thereto.

7. A device for spacing the two rails of a track comprising a bar with slideable jaws mounted thereon to engage both of the rails 65 and hold them in fixed relation to the bar, wedging keys adapted to lock said jaws at any desired point along the bar, and a hook pivoted to the bar and adapted to engage the adjacent railway sleeper so as to hold the 70 bar in fixed relation thereto.

8. A device for spacing the two rails of a track comprising a bar with a slide thereon, said slide having a jaw adapted to engage the base of the rail and a sleeve surrounding 75 the bar, said slide also having a tapering transverse slot adjacent to the surface of the bar, and an adjustable wedge lying in said slot and adapted to lock the slide to the bar at any desired point of adjustment, the 80 surface of the bar adjacent to the slide being uniform.

9. A device for spacing the two rails of a track, comprising a bar with one end bent over to form a jaw, three sliding members 85 on the bar each carrying a jaw, and a wedge engaging each of the sliding members and adapted to lock the same at any desired position along the bar, the surface of the bar adjacent to said wedges being uniform. 90

10. In a device of the class described, a bar having one end bent over to form a hook, the remainder of the bar being continuous and uniform in cross section, three sliding members surrounding the bar, each said 95 member having a transverse slot adjacent to the bar, and respective wedges in said slots adapted to lock the said members by their wedging action at any desired point of adjustment along the length of the bar. 100

In testimony whereof, I have subscribed my name.

JOHN W. KENDRICK.
